United States Patent Office

Des. 216,209
Patented Dec. 2, 1969

216,209

TRICYCLE

Laurie J. Campbell, Erie, Pa., assignor to Louis Marx
& Company, Inc., a corporation of New York

Filed Apr. 3, 1969, Ser. No. 16,574

Term of patent 14 years

Int. Cl. D12—11

U.S. Cl. D34—15

FIG. 1

FIG. 2

FIG. 3

FIG. 4

FIG. 5

FIG. 1 is a side view of a tricycle in accordance with my new design;

FIG. 2 is a top plan view thereof;

FIG. 3 is a front view thereof;

FIG. 4 is a bottom plan view thereof; and

FIG. 5 is a rear view thereof.

I claim:

The ornamental design for a tricycle, as shown.
